TOOL POST ASSEMBLY FOR MACHINE
TOOLS

Roy L. Dorn, Riverdale, Calif.

Application October 10, 1944, Serial No. 558,006

4 Claims. (Cl. 82—37)

1

My invention relates to an adjustable post for a lathe, a shaper, and similar tools, the post being adapted to support the cutting tool holder.

The object I have accomplished is the construction of a post for holding, or supporting the cutting tool holder used on a lathe, a shaper, or other similar tools wherein the adjustment of the height, angle of cutting, or rake of the tool can easily be adjusted.

These, and other objects hereinafter referred to are accomplished by means of the device herein described and illustrated on the accompanying drawing in which

Fig. 1 is a view of the T-slot member on the compound rest of the lathe, the T-slot being adapted to hold the adjustable tool post.

Fig. 2 is an enlarged view of a block having a concave face adapted to cooperate with the convex base of the post, and having a hole therethrough adapted to fit over, and around the post.

Fig. 3 is a fractional view of the tool post having an approximately ellipsoid base, the top face of said base being adapted to fit within the concavity in the face of the block shown in Fig. 2.

Fig. 4 is a view of the tool post and its base, having parts cut away to better show the form of the base in section, and having the block shown in Fig. 2 assembled therewith, said block also being shown in section.

Fig. 5 is a face view of either of the discs shown in Fig. 6.

Fig. 6 shows three cooperating discs assembled, but slightly spaced apart to emphasize the fact that each disc is independent of the others.

Fig. 7 is a separate view of the center disc shown in Fig. 6, showing the center hub, or core which is constructed integral with the center disc, portions thereof being cut away to show the interior design of the hub.

Fig. 8 is a cross sectional view of the disc assembly shown in Fig. 6 along sectional line 8—8 in Fig. 6.

Fig. 9 is an enlarged tool post having a modified form of base, and has assembled therewith the tool holder and adjusting discs.

Fig. 10 is a tool post similar to the one shown in Fig. 9, the view being at right angles to the view shown in Fig. 9.

Fig. 11 is a tool holder adapted to fit into the slot in the tool post.

Fig. 12 shows the top face of the top disc, being a concave surface.

Fig. 13 is a rocker block, the curved bottom being adapted to fit within the concave surface of the disc shown in Fig. 12.

Fig. 14 is a modified form of the face of the disc, inclines being substituted for threads, the inclines being spiral and rising in a clockwise direction.

2

Fig. 15 is similar in all respects to Fig. 14 except the spiral of the inclines thereon describe an anti-clockwise direction.

Fig. 16 is a block adapted with cooperating blocks to vary the tool post in a leaning position.

Fig. 17 is another block to be used with the base of the tool post, and other blocks, to vary the vertical angle of the tool post.

Referring to the drawing, I have shown in Fig. 1 a tool post support 20 having a T-slot 21, which slot 21 runs lengthwise within said tool post support 20. T-slot 21 is adapted to receive and hold tool post 30. Tool post 30 has an approximately ellipsoid base 37 attached thereto as shown in Figs. 3 and 4. Block 34, shown in Fig. 2, a sectional view thereof being shown in Fig. 4, can be assembled with tool post 30 by placing block 34 over tool post 30 and through hole 35 in block 34, the concave face 36 of said block being adjacent to the upper surface of the ellipsoid base 37 of tool post 30. Assembled base 37 and block 34 should be of such size that they can easily enter and slide within T-slot 21. Tool holder 19 shown in Fig. 11 can be inserted in slot 18 after positioning discs 41, 42 and 43 shown in Figs. 6 and 8, and in Fig. 9 between tool post support 20 and tool holder 19.

Rocker block 49, shown in Figs. 9 and 13, is inserted within slot 18 under tool holder 19 with the curved surface thereof adjacent to the concave face of disc 41, this arrangement being adapted to adjust the angle of the tool holder by moving rocker block 49 so that the plane of its upper surface is at the selected angle with a horizontal line. Then by tightening set screw 24 shown in Fig. 9, that is by screwing it down firmly on the top of the tool resting on rocker block 49, the tool holder, the adjusting discs, and the tool post are all tightly clamped to tool support 20, and to the compound rest of the lathe, not shown in the drawing, to which tool support 20 is attached.

It is noted that in tool posts and assemblies now in use the rocker block as described is in use and it permits the tool holder to be tilted on one plane only, but the post is constantly rigid in a vertical position. In my invention I have provided for the leaning of the tool in any direction desired, and have provided the following elements to accomplish that result. Under face 39 of base 37 is convex to enable post 30 to be leaned in any direction. Upper face 38 of base 37 is likewise convex for the same purpose. To hold post 30 firmly when the selected position or leaning of the post is attained, I have provided block 34 which has a concave face 36. Concave face 36 fits over convex surface 38 of base 37. It will be noted that face 36A, being the upper face of block 34, is a plane which can rest against the plane under surface of flanges

20A forming T slot 21, and any direction post 30 may lean the convex surface 38 of base 37 engages the concave surface 36 of block 34 and will make a firm contact with tool post support 29. Hole 35 in block 34 is large enough so that block 34 will not interfere with the leaning position of the post within reasonable limits.

Hub 46 in hub 45 describes two frustums of cones joined at the smaller diameter, the two frustums forming hole 46. When disc 43 is assembled with tool post 30 by passing the tool post through hole 46, such hub 45 will not interfere with the leaning of tool post 30. Hub 45 has a uniform outside diameter and is adapted for discs 41 and 42 to be threaded thereon, so that when thus assembled discs 41, 42 and 43 are concentric with each other.

Members 41, 42 and 43 are adjusting discs. Discs 41 and 42 have faces not on parallel planes but are approximately wedge shaped. Each of discs 41 and 42 have center holes 44 therein which will encircle hub 45. It is noted that when discs 41 and 42 are assembled with disc 43 between them, discs 41 and 42 can be rotated in the same or in opposite directions on hub 45. The space between tool holder 19 and tool post holder 20 is partially filled with rocker 49, and discs 41, 42 and 43. If additional space is still unoccupied, not required for adjustments, it can be filled in with washers 48. However in practice such washers are seldom needed. It is noted when such space between the tool holder and the support for the tool post is practically filled, by moving discs 41 and 42 relative to each other, the angle of the plane on which tool holder 19 rests can be angled in any selected position. When the angle desired has been secured, minute adjustments as to the height of the tool holder is made as follows: Adjacent faces of discs 41, 42 and 43 have scroll threads 40 thereon, which in one position will fit together, but when rotated independently, the threads will ride on the top of each other. Thus, when the leaning adjustment has been secured, by holding discs 41 and 42 from rotating, and rotating disc 43, a slight vertical adjustment can be obtained. When the angle adjustment and the vertical adjustment of the tool holder and tool post is secured, cap screw 24 can be tightened, the top of tool 19 resting on block 49, and thus clamp the entire assembly together.

In Figs. 14 and 15 I have shown a modified form for the faces of discs designated 43X and 43Y. In Fig. 14 disc 43Y shows four spiral inclines, 40A, 40B, 40C and 40D. The high portion of each incline ends at the line of a diameter of the disc, said diameters being at right angles to each other. Disc 43X shows the same character of face except that the inclines run anticlockwise instead of clockwise. These inclines are designated 40W, 40X, 40Y and 40Z. When discs 41 and 42 having these modified faces are assembled with the spiral inclined faces adjacent, and concentric with each other it will be noted that by rotating either disc without a corresponding rotation of the other, will move the discs slightly apart or together, depending on the direction the discs are rotated, and this action is adapted to make slight adjustments in the height of the tool holder from the base, or tool post support. In use discs 43X and 43Y are substituted for discs 41, 42 and 43, heretofore described. It is noted that while I have shown four of these inclines on the face of each disc in Figs. 14 and 15, the number of inclines can be greater or less with

5 approximately the same efficiency. It is also noted that such inclines can be provided on the adjacent faces of discs 42 and 43 if desired. In thickness of discs 43X and 43Y can be uniform, or wedge shaped if desired.

Referring more minutely to Figs. 9, 10, 16 and 17, a slightly different mechanical combination is used to tilt post 30 in the direction desired. Base 37A has a lateral, and a transverse cylindrical 10 convex surface on the underside of the base instead of the spherical convex surface shown in Figs. 2, 3 and 4. The longitudinal center lines of those convex surfaces are at right angles. Upper surface 38A of base 37A is likewise a cylindrical convex surface the center line thereof being parallel to the center line of one of the cylindrical convex surfaces 39B. On the top of base 37A is fitted a block 61, having a cylindrical concave surface 61A, the curve of which neatly fits on the upper surface 38A of base 37A, so it can slide thereon. The upper face of block 61 consists of two portions extending lengthwise of the block, said portions being designated 61B and 61E, the surfaces of said portions 61B and 61E being curved 15 with the diameter of the curve at right angles to the diameter of the under concave surface 61A. Parallel with the lineal diameter of under face 61A and firmly attached to the upper face of block 61, is a rectangular guide 61C. A round hole 61D is made through guide 61C and block 61, so that it can be threaded loosely over post 30. A third block, shown in enlarged form in Fig. 17, has a channel 62A which loosely fits over rectangular guide 61C, and an opening 62D which extends through block 62, the opening being large enough to receive slideway 61C. The under surface 62B of block 62, is curved with the diameter of the curve at right angles to the side of opening 62D. Block 62 is adapted to be assembled with 20 block 61, the concave face of block 62 resting on the convex face of block 61 and to slide thereon. Upper face 62C of block 62 is a plane which, when assembled rests against the under faces of flanges 20A on post support 20. The rectangular opening 62D in block 62 is of such size that post 30 can easily pass therethrough.

In operating this device base 37A is attached to the lower end of post 30; block 61 is threaded on post 30 so that the cylindrical concave surface of block 61 engages the convex cylindrical surface of base 37A. Block 62 is then threaded on post 30 so that its under cylindrical concave surface 62B is adjacent to the upper convex surface 61B of block 61. Rectangular guide 61C should engage recess 62A and opening 62D. The assembled post 30, base 37A, and blocks 61 and 62 are then inserted in slideway 21. It will be noted that with this combination post 30 can be rocked in any direction. Discs 41, 42 and 43 are then threaded over post 30, and washers 48 are positioned between disc 42 and flanges 20 if necessary. Rocker 49 is inserted in slot 18, and tool 19 is likewise placed in slot 18, and when post 30 is positioned at the desired angle cap screw 24 is tightened on cutting tool 19. The cutting tool is thus held rigid in the selected position.

Having described my invention, I claim as new and ask for Letters Patent:

1. In a device of the character described, a tool post adapted for anchoring a tool holder thereto, the tool post having a base attached thereto, the base having the under surface curved both laterally and longitudinally, the upper face of the base being curved in one direction only; an independent block having the under surface

curved to neatly fit the upper surface of the base and adapted to slide thereon; the upper surface of said first independent block being curved with the diameter of the curve at right angles to the diameter of the under curve of the first independent block, a rectangular key extending across the upper face of the first independent block at right angles to the diameter of the curve of the upper face of the first independent block; a second independent block approximately rectangular in form having a curved surface on the under face adapted to fit on to, and to slide on the upper face of the first independent block, and a key way on the under side of the second independent block adapted when assembled with the first independent block to receive the key on the first independent block, holes through the first independent block and the second independent block adapted for the tool post to loosely pass therethrough, the device having a tool post support the support having an inverted T slot therein, adapted for the tool post base, the first independent block and the second independent block when assembled together to pass within said inverted T-slot, the assembled base, the first independent block and the second independent block when within the slot being adapted to permit the post to lean within a limited degree in any direction from the vertical.

2. In a device of the character described, a tool post having a slot therein adapted to receive a tool holder and a rocker, a tool post support having an inverted T-slot therein, a base on the tool post adapted to enter the inverted T-slot, the base of the post being adapted to permit the post to lean a limited distance from the perpendicular; a plurality of discs adapted to encircle the post and to extend approximately from the tool post support to the rocker, one of said discs having a hub thereon with a hole through the hub describing two frustums of a cone joined at the smaller diameter, the hole being adapted for the post to pass therethrough, the hole adapted for the post to lean in any direction at a limited angle from the perpendicular, the disc adjacent to the tool post support being adapted to slide on said support, one of the discs being wedge shaped in thickness, and being adapted to be rotated independently of the other discs, and adapted when revolved to locate a position where it will fill the space between the tool post support and the rocker, screw means adapted to clamp the tool holder, the rocker, and the discs to the tool post support.

3. In a device of the character described, a tool post having a slot therein adapted to receive a tool holder and a rocker, a tool post support

having an inverted T-slot therein, the base of the post being adapted to permit the post to lean in a limited degree from the perpendicular, a plurality of discs having holes through the centers thereof adapted to surround the tool post and to rest, one on the top of another between the rocker and the tool post support, a plurality of the discs being wedge shaped as to thickness, each disc being adapted to rotate on its axis independently of the other discs, a plurality of the discs having involute threads on the faces of the discs adapted when the threaded faces are adjacent to each other for the crests of the threads in one disc to be within the valley of the threads of the adjacent cooperating disc, and adapted when one of the discs is rotated independently of the other disc for the threads of one disc to ride on the sloping surface of the threads on the adjacent disc, and adapted to force the cooperating discs apart.

4. In a device of the character described, a tool post having a slot therein adapted to receive a tool holder and a rocker, a tool post support having an inverted T-slot therein, the base of the post being adapted to permit the post to lean to a limited degree from the perpendicular, a plurality of discs having holes through the centers thereof adapted to be threaded on to the tool post and to rest, one on the top of another between the tool post support and the rocker, each disc being adapted to rotate on the post as an axis independently of the other discs, a plurality of the discs having involute threads on the faces of the discs, said threads being adapted when the threaded faces of two discs adjacent to each other for the crest of the thread in one disc to be within the valley of the thread on the adjacent disc, and adapted when one disc having a thread thereon is rotated independently of the cooperating disc, for the thread of one disc to ride on the sloping surface of the thread on the adjacent disc, and adapted to force the cooperating discs apart.
